Attorney

UNITED STATES PATENT OFFICE.

HERBERT BRADFORD RICKETSON, OF PROVIDENCE, RHODE ISLAND.

BASEBALL-CURVER.

1,332,303.

Specification of Letters Patent.

Patented Mar. 2, 1920.

Application filed June 11, 1919. Serial No. 303,342.

To all whom it may concern:

Be it known that I, HERBERT B. RICKETSON, a citizen of the United States, residing at Providence, in the county of Providence and State of Rhode Island, have invented certain new and useful Improvements 5 in Baseball-Curvers, of which the following is a specification, reference being had to the accompanying drawings.

10 This invention relates to certain improvements in base ball curvers and it is an object of the invention to provide a novel and improved device of this general character which may be readily applied to a digit of 15 a hand and which serves to impart the desired spin or rotation to a ball when thrown to cause said ball to travel in a curve.

The invention consists in the details of construction and in the combination and arrangement of the several parts of my improved base ball curver whereby certain important advantages are attained and the device rendered simple, non-expensive and otherwise more convenient and advantageous 25 for use, as will be hereinafter more fully set forth.

The novel features of my invention will hereinafter be definitely claimed.

In order that my invention may be the better understood, I will now proceed to describe the same with reference to the accompanying drawings, wherein—

Figure 1 is a view in perspective of a base ball curver constructed in accordance with an embodiment of my invention and in applied position, the coacting hand being indicated by dotted lines; and

Fig. 2 is an enlarged view partly in section and partly in elevation of the device 40 as herein disclosed.

As disclosed in the accompanying drawings B denotes a band, preferably elastic, adapted to be applied to a digit of a hand and disposed transversely of said band B 45 and secured thereto is an elongated metallic plate P. At its longitudinal center the plate P is provided with the outstanding bead or corrugation 1, substantially semi-circular in cross section. The bead or corrugation 1 affords a hump for contact with the periphery 50 of the ball and serves to materially increase the spin or rotation of said ball so that the same may be thrown to travel in a curve.

In practice the band B is applied to either 55 the first or second finger of the hand of the throwing arm, and between the first and sec-

ond joints of such finger with the corrugation or bead in contact with the ball. The desired curving of the ball in its travel is materially facilitated by the increased rotation imparted to the ball by my improved device as the ball leaves the hand. 60

The bead or corrugation 1 is substantially rigid and extends in a direction circumferentially of the band B and the functioning 65 of the device is materially enhanced by the cross sectional configuration of the bead or corrugation 1.

The opposite end portions of the plate P are returned to afford the inwardly directed 70 extensions 2 overlying the inner face or surface of the band B and said band B is clamped between the extensions 2 and the plate P proper whereby said plate P is effectually maintained in applied position. 75

From the foregoing description, it is thought to be obvious that a base ball curver constructed in accordance with my invention is particularly well adapted for use by reason of the convenience and facility with 80 which it may be applied and assembled, and it will also be obvious that my invention is susceptible of some change and modification without departing from the principles and spirit thereof, and for this reason I do not 85 wish to be understood as limiting myself to the precise arrangement and formation of the several parts herein shown in carrying out my invention in practice except as hereinafter claimed. 90

I claim:

1. A base ball curver comprising an elongated plate having an outstanding bead extending transversely thereacross, said bead being substantially semi-circular in cross 95 section, and means for attaching the plate to a digit of a hand with the longitudinal axis of the plate extending longitudinally of the digit.

2. A base ball curver comprising a band 100 adapted to surround a digit of a hand, a plate extending transversely of the band and secured thereto, said plate having a transversely extending corrugation providing an outstanding bead disposed circumferentially of the band. 105

In testimony whereof I hereunto affix my signature in the presence of two witnesses.

HERBERT BRADFORD RICKETSON.

Witnesses:

CHARLES W. GRAFTON,
JAMES REILLY.
